UNITED STATES PATENT OFFICE.

BURR F. BARNES, OF JERSEY CITY, NEW JERSEY.

TILTING BIN.

SPECIFICATION forming part of Letters Patent No. 755,605, dated March 29, 1904.

Application filed July 11, 1903. Serial No. 165,158. (No model.)

To all whom it may concern:

Be it known that I, BURR F. BARNES, a citizen of the United States, residing at Jersey City, in the county of Hudson and State of New Jersey, have invented certain new and useful Improvements in Tilting Bins; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in tilting bins comprising series of bins or boxes having pivotal pins on the sides so positioned as to counterbalance the same and in the provision of a latch provided to normally hold the bin in place when tilted down or opened and so arranged that by lifting the latch the drawer or bin may be removed.

The invention consists, further, in various details of construction and in combinations and arrangements of parts, which will be hereinafter fully described and then specifically defined in the appended claims.

My invention is illustrated in the accompanying drawings, which, with the letters of reference marked thereon, form a part of this application, and in which—

Figure 1 is a front elevation of a portion of a cabinet embodying my improved bins or boxes. Fig. 2 is a vertical sectional view through the cabinet and bins, showing one of the bins tilted in dotted lines. Fig. 3 is a horizontal sectional view through one of the bins or drawers and adjacent parts of the frame, and Fig. 4 is a detail view of the latch.

Reference now being had to the details of the drawings by letter, A designates a suitable cabinet or housing for the bins, which may be of any desired shape and size and have as many bins or boxes mounted therein as may be desired. In the present instance I have illustrated but two bins in my cabinet, and each bin is designated in the drawings by letter B. The sides of each bin are recessed, as at B', in from the bottom, and C is a socket-plate fitted in said slot and in which

the pivot-pin D has a bearing, said pivot-pin being supported by the frame of the cabinet. Said pivot-pins are so positioned with relation to the boxes or bins which they support that said bins may be allowed to tilt in the 55 positions shown in dotted lines in Fig. 2 of the drawings, whereby access may be had to the same, or they may be removed from the frame, if desired. Each bin is similarly mounted upon pivot-pins, as described, and 60 in order to prevent the pin from coming out of the cabinet or casing I provide a latch comprising a plate or bar E, one end of which is pivoted at E' to the casing and having a widened portion E² intermediate its contracted 65 ends, as shown in Fig. 4 of the drawings. The pivot-pin supporting the slide is mounted in the frame near one end of the bin, and a pin F is supported by the frame near the opposite front edge of the opening of the 70 frame in which the box or bin is mounted, and the widened portion of said latch when in the position shown in solid lines in Fig. 4 is designed to rest in front of the rear upper end of the pin when the latter is thrown in 75 an open relation; but when it is desired to remove the bin from the frame said latch may be raised and the bin withdrawn from the frame. When the bin is turned back into the frame or cabinet, it rests upon a cross-piece H and is held closed by the latch, it being necessary to raise the latch when it is desired to open the bin, said latch serving a twofold purpose of normally holding the bin locked and also preventing the same from being removed when the bin is opened.

A display-front for each of the bins or boxes is provided by having a partition I held in position adjacent and parallel to the front of the box or bin, the lower end of said partition being held by means of a rib K, while the upper end is held by means of a hook N, seated in a pin on the upper edge of said partition. By the provision of this display-front the bin may have the appearance of being 85 filled when in reality the bin may be only partially filled, when the space intervening between the partition and the display-front may be filled to the top with a sample of the contents of the bin.

The operation of my bin is simple and is as follows: When it is desired to open the same, the latch is raised and the bin allowed to tilt down in the position shown in dotted lines 5 and arrested from further removal or withdrawal by means of the latch catching against the upper edge. When for any purpose it may be desired to remove the bin from the casing, said latch may be raised and the bin 10 removed.

While I have shown a particular construction of apparatus embodying the features of my invention, it will be understood that I may make alterations in the detailed construction of the same without departing from the spirit of the invention.

Having thus fully described my invention, what I claim as new, and desire to secure by Letters Patent, is—

1. A cabinet of bins comprising a frame, pivot-pins supported by the latter, bins pivotally mounted upon said pins, and a tilting latch adapted to normally engage the front swinging edge of the bin to hold the same within the frame and also to engage the rear edge of the bin when opened to hold the same within the frame, as set forth.

2. A cabinet of bins comprising a frame, each bin having a slotted side, pivot-pins supported by the frame and engaging said slots, a latch pivoted to the frame adjacent to the front of the bin and adapted to normally rest in the path of the swinging bin to hold the

same locked, and designed, as the bin is opened, to hold the same within the frame, as set forth. 35

3. A cabinet of bins comprising a frame, bins, each of which has slotted sides, suitable socket-plates secured therein, pivot-pins carried by the frame and engaging said plates, a pivoted latch mounted upon the front of the 40 frame and having a widened portion adapted to normally engage in the path of the swinging bin when closed, and adapted, when the bin is open, to engage the rear upper edge of the bin and hold the same in the frame, as set 45 forth.

4. A cabinet of bins comprising a frame, bins therein, each of which is provided with slots in its opposite sides cut in from the bottom, socket-plates in said slots, pivot-pins supported by the frame and engaging said plates, a partition mounted parallel with the front face of the bin, a hook carried by the bin and engaging said partition, a gravity-latch pivoted in front of each bin and having a portion 50 thereof projecting in the path of the bin, whereby the latter may be held locked when closed and hold the bin from withdrawal from the frame when open, as set forth.

In testimony whereof I hereunto affix my 55 signature in presence of two witnesses.

BURR F. BARNES.
